Primary Examiner — T Chase Nelson

(57) **CLAIM**

The ornamental design for a spectacle case, as shown and described.

DESCRIPTION

1. Spectacle case

1.1 : Front

1.2 : Back

1.3 : Left

1.4 : Right

1.5 : Top

1.6 : Bottom

1.7 : Perspective

1.8 : Perspective view showing the design in an open position

1 Claim, 8 Drawing Sheets(56)
